UNITED STATES PATENT OFFICE.

CHARLES L. GOODRUM, OF NEW YORK, N. Y., ASSIGNOR, BY MESNE ASSIGNMENTS, TO
WESTERN ELECTRIC COMPANY, INCORPORATED, A CORPORATION OF NEW YORK.

TELEPHONE SWITCHING SYSTEM.

1,245,900.

Specification of Letters Patent.

Patented Nov. 6, 1917.

Application filed September 7, 1915, Serial No. 49,289.

To all whom it may concern:

Be it known that I, CHARLES LANE GOODRUM, a citizen of the United States, residing at New York, in the county of New York, 5 and State of New York, have invented certain new and useful Improvements in Telephone Switching Systems, of which the following is a full, clear, concise, and exact description.

10 This invention relates to telephone switching systems, and more particularly to improvements in order wire circuits as used in connection with the handling of trunk service between telephone exchanges, and has 15 for its objects, first, to improve the telephonic transmissions, second, to prevent the possibility of messages becoming confused, and third, to reduce the length of regular order-messages as transmitted by an "A" 20 operator in requesting a trunk assignment from a "B" operator.

In accordance with this invention, an order wire circuit composed of individual line circuits from a plurality of exchanges 25 for service to a "B" position at another exchange, is provided with switching relays, signals individual to each exchange, and a tone signaling current supply. An operator's telephone circuit at the "B" position 30 is normally disconnected from the order wire circuit and is not capable of being connected to more than one of the plurality of entering order wire line circuits at the same time. The switching operations are under 35 the control of "A" operators at any of the distant exchanges, and take place automatically when an order wire key is depressed in the usual way. At the "B" position a signal lamp is lighted during the time the "B" 40 operator's telephone circuit is connected to a distant exchange, thereby indicating from which exchange an order is being received.

In the drawing illustrating this invention there is shown at 1 an "A" operator's telephone circuit and an order wire key 6 assumed to be located at an originating exchange, and similar equipment may be assumed to be present at the points 2 and 3 which represent other originating 50 exchanges.

Each of the order wire line circuits extending to exchanges 1, 2 and 3 are provided with similar individual equipment consisting of relays 10, 11 and signal lamp 55 12 for exchange number 1; relays 30, 31 and

lamp 32 for exchange number 2; and relays 50, 51 and lamp 52 for exchange 3. The master relay 35 being common to the devices associated with the three line circuits, a condenser in each side of the line circuits, 60 indicated as 17 and 18 in the line to exchange 1, are employed for the purpose of excluding battery current from the "B" operator's telephone circuit and from the secondary winding 44 of the transformer 43. 65

In describing the operation of this system let it be assumed that a subscriber, whose line terminates in exchange 1, requests to be connected with a subscriber whose line terminates in the exchange at 70 which the "B" operator's circuit 25 is located. An "A" operator at exchange 1 depresses the order wire key 6. The closure of contacts 7 and 8 of this key establishes a circuit from battery 40, through the separate windings of relay 10 and line conductors 4 and 5, completing circuit through the "A" operator's telephone set at exchange 1, thereby effecting the operation of the relay 10. Closure of contacts 9 on relay 10 now 75 completes a series circuit from battery 40 through switching relay 11 and master relay 35 by way of conductor 39, contacts 36 of relay 35 and conductors 19, 42 and 23. Switching relay 11 now operates slightly in 80 advance of master relay 35 as a result of the closed copper secondary on the core of the master relay. This difference in time between the operation of the two relays permits the contacts 13 of the relay 11 to have 85 established a shunt path around the contacts 36 of relay 35 before the latter contacts are opened. Therefore, after the relay 35 has operated, the path formed by contacts 13 of relay 11 and conductor 20 are substituted for the first path formed by contacts 36 of relay 35 and conductors 42, 19 and 39. Signal lamp 12 connected in bridge 90 on the winding of relay 11 by means of conductors 42 and 45 will accordingly be lighted during the time the series circuit is retained through the relays 11 and 35. The opening of contacts 16 of relay 11 disconnects the tone signaling current from this line circuit, and contacts 14 and 15 of this 95 relay close a talking circuit by means of conductors 21, 22, 4 and 5 between the "B" operator's telephone circuit 25 and the "A" operator's telephone circuit at exchange 1. The signal lamp 12 remaining lighted, the 100 105 110

"A" operator may omit the name of the originating exchange and only give the telephone number of the subscriber's line for which a trunk is desired. During the time 5 this talking circuit is retained between exchange 1 and the "B" operator's telephone circuit, the exchanges 2 and 3 are prevented from securing connection with the "B" operator in the following manner: Assume 10 that an "A" operator's equipment, similar to that shown at exchange 1, is connected in bridge on line conductors 26 and 27 at exchange 2, depression of the order wire key would effect the operation of line relay 30 in 15 a manner similar to that already described for the line relay 10 associated with the line circuit to exchange 1. Although contacts 29 of relay 30 would now be closed, switching relay 31 would not operate on account of 20 its circuit, by way of conductors 33 and 34, being open at the contacts 37 of master relay 35. The failure of relay 31 to operate permits the tone signaling current from transformer 43 to traverse contacts 28 of this 25 relay and complete circuit over the line conductor 27, the operator's telephone circuit at exchange 2, line conductor 26, one winding of relay 30, thence through the battery 40 to earth, thereby indicating to 30 the seeking "A" operator that the "B" operator is busy. The same results would be present with respect to the order wire circuit to exchange 3 in case an "A" operator at that point should seek connection with 35 the "B" operator. Upon the order wire key 6 being released at exchange 1, relays 10, 11 and 35 are released and the signal lamp 12 is extinguished. The operations for either one of the exchanges 1, 2 and 3 are 40 identical with respect to each other. Therefore, during the time either one of the exchanges may be connected to the "B" operator's telephone circuit, the other two exchanges will be locked out and the busy test 45 signaling current applied to the line circuits.

This system may be extended to cover any 50 number of originating exchanges by placing additional contacts on the master relay 35 and equipping each additional order wire line circuit with a line relay, switching relay and signal lamp as described in connection with the circuits shown in the drawing.

For the purpose of simplifying the circuit arrangement in the drawing, several batteries 40 and several transformer sets 43 are shown. It will be understood, however, that only one battery and one transformer set will be necessary in the operation of this system.

60 What is claimed is:

1. In a telephone switching system, a plurality of ordering stations, an order receiving station, a line circuit extending from each of said ordering stations to said order receiving station, an operator's circuit at

said order receiving station, a source of signaling current at said order receiving station normally connected to the terminals of each of said lines, and switching means individual to and operated over each of said line circuits for associating said operator's circuit therewith, and for disconnecting said source of signaling current therefrom. 70

2. In a telephone switching system, a plurality of ordering stations, an order receiving station, a line circuit extending from each of said ordering stations to said order receiving station, an operator's circuit at said order receiving station, switching means individual to each of the said lines for associating said operator's circuit therewith to the exclusion of the remaining ones of said line circuits, a source of signaling current at the order receiving station normally connected with the terminals of each of said line circuits through switching means individual thereto, and means controlled by any one of said switching means for rendering said source of signaling current ineffective with respect to the line circuit associated 80 with the operated switching means but effective with respect to the remaining line circuits. 85

3. In a telephone switching system, a plurality of ordering stations, an order receiving station, a line circuit extending from each of said ordering stations to said order receiving station, an operator's circuit at said order receiving station, switching means individual to and operated over each of said line circuits for associating said operator's circuit therewith, a source of signaling current at the order receiving station normally connected with the terminals of each of said line circuits through the switching means 95 individual thereto, and means controlled by the operation of an individual switching means for disconnecting said signaling current from the line associated therewith and for preventing the operation of the remaining ones of said switching means. 100

4. In a telephone switching system, a plurality of ordering stations, an order receiving station, a line circuit extending from each of said ordering stations to said order receiving station, an operator's circuit at said order receiving station, a signal at said order receiving station for each of said line circuits, switching means individual to and controlled over each of said line circuits for 115 connecting said operator's circuit therewith, a source of signaling current at said order receiving station normally connected to the terminals of each of said line circuits through switching means individual thereto, 120 means operated by any one of said switching means for operating the signal associated therewith and retaining said signal effective during the period said operator's circuit is held connected with an associated 125

line circuit, and means controlled by the operation of an individual switching means for disconnecting said signaling current from the line associated therewith and for preventing the operation of the remaining ones of said switching means.

5. In a telephone exchange system, a plurality of ordering stations, an order receiving station, a line circuit extending from 10 each of said ordering stations to said order receiving station, an operator's circuit at said order receiving station, a signaling device at said order receiving station for each of said lines, switching means individual to 15 and operated over each of said lines for connecting the operator's circuit therewith and for operating the said signaling device associated therewith, a source of current at the order receiving station, switching means at 20 the order receiving station and common to all of said line circuits for controlling the application of said source of current, and means under the conjoint control of the said common switching means and any one

of the said individual switching means for 25 excluding the connection of the said operator's circuit with the remaining line circuits.

6. In a telephone exchange system, a plurality of ordering stations, an order receiving station, a line circuit extending from 30 each of said ordering stations to said order receiving station, a signaling device at said order receiving station individual to each of said lines, an operator's circuit at said order receiving station, switching means individual to and controlled over each of said line circuits, means controlled by the operation of any one of said individual switching means for operating said signaling device associated therewith and for connecting the 35 operator's circuit with the associated line, and means at said order receiving station for disabling said signaling device associated with the remainder of said lines.

In witness whereof, I hereunto subscribe 45 my name this 2nd day of September A. D., 1915.

CHARLES L. GOODRUM.
